MILK CAN COVER

Louis J. Hois and Alexander C. Sladky, Milwaukee, Wis., assignors to Geuder, Paeschke & Frey Company, Milwaukee, Wis., a corporation of Wisconsin

Application November 27, 1936, Serial No. 112,938

3 Claims. (Cl. 220—24)

This invention relates in general to milk cans and more particularly to a cover or closure therefor.

Among the objects of the invention is the provision of a milk can cover construction of such character that a complete closure and protection is had for the opening of the can and this in such a manner that the maximum in the way of sanitation is realized and yet the cover may be readily handled and removed and also affords the desirable insulation between the cover and the contents of the can.

Another object is to provide a can cover construction which is simple and durable in its nature, susceptible of convenient and economic manufacture from material and by means of facilities readily available and reliable and convenient in use.

Other objects and advantages reside in certain novel features of the construction, arrangement and combination of parts which will be herein-after more fully described and particularly pointed out in the appended claims, reference being had to the accompanying drawing forming a part of this specification, and in which:

Figure 1 is a fragmentary view in transverse vertical section showing a milk can or container equipped with a cover embodying the present invention;

Figure 2 is a view of a portion of the structure shown in Figure 1 but showing the same on an enlarged scale for the sake of illustration; and

Figure 3 is a view of the cover removed from the can or container and showing the same in bottom plan.

Referring to the drawing, the numeral 1 designates generally a milk can or container of any standard or conventional construction but preferably having a contracted neck 2 above which is an outwardly flaring flange or section 3 terminating in a rolled bead 4 and defining the opening at the top of the can or container.

Cooperable with the container is a cover designated generally at 5 and having as its major elements a plug-like closure with which is assembled an umbrella top 7, the plug and top being interconnected to provide a unitary cover assembly applicable to and removable from the container as a unit.

The plug-like member of the cover comprises a shell-like body designated generally at 8 and consisting of a lower cylindrical section 9 and an upper outwardly flaring section 10 dimensioned and proportioned to snugly fit and completely fill the opening to the container defined respec-

tively by the contracted neck 2 and its outwardly flaring extension or flange 3. At the bottom of the cylindrical section 9 there is an integral lower end or closure plate 11. The corner between the end plate 11 and the cylindrical section 9 is reinforced by an annular reinforcing metal ring 9' of angular cross section which is secured in place preferably by spot welding. The outwardly flaring upper section 10 of the shell-like plug has integral therewith a flange 12 which curves upwardly and outwardly and then downwardly.

The umbrella top 7 consists of a flat top plate 13, the periphery of which is provided with an outwardly and downwardly curving annular flange-like structure 14, the lower portion of 15 which fits flush against the downwardly and outwardly curving portion of the flange 12. The lower portion of the flange 12 is provided with a rolled bead structure 15 into which the lower extremity 16 of the flange 14 is interseamed or interfitted. The bead structure 15 and its interfitting and interseamed extremity 16 may be reinforced by wire 17. The bead 15 terminates in an inwardly extending edge portion disposed close up against the outer face of the downwardly curving annular flange-like structure 14. A ring of solder designated at 18 is provided between the edge of the bead structure 15 and the flange structure 14. The solder 14 is out of contact with the contents of the container to which the cover is applied.

It will be noted that the umbrella cover 5 and the plug-like member 8 define a completely closed and dead air space 20 which imparts to the cover the desired heat insulating properties without materially increasing its weight or disturbing its balance.

The cover may be conveniently grasped and handled and consequently easily applied to and readily removed from a milk can or container. When it is applied it completely closes the entrance to the can and does this in such manner that there are no spaces or crevices between the cover and the can in which foreign matter or contaminating medium of any kind may find its way. The top of the cover is such as to shed water, ice or snow and contains or presents no depressions into which dirt or snow may accumulate. In general, the cover combines all of the advantages of the various types previously known while avoiding the disadvantages of each.

While we have shown and described one construction in which our invention may be advantageously embodied, it is to be understood that this construction has been selected merely for

the purpose of illustration or example, and that various changes in the size, shape and arrangement of the parts may be made without departing from the spirit of the invention or the scope 5 of the subjoined claims.

The invention claimed is:

1. A cover for a container of the type having a flaring neck at its upper open end and comprising a plug-like closure member and an umbrella top, 10 the plug-like closure member being constituted of an imperforate shell designed to snugly fit in and completely fill the opening at the upper end of the container and having an integral lower end wall and also having an integral flange at 15 its upper end which curves upwardly and outwardly and then downwardly about and beyond the flaring neck of the container, said umbrella top consisting of an imperforate metal plate having an integral outwardly and downwardly curv- 20 ing annular flange, the edges of said flanges being interconnected, said top and said closure member defining a completely closed dead air space to render the cover heat insulating.
2. A cover for a container of the type having an upper open end and comprising a plug-like closure member and an umbrella top, the plug-like closure member being constituted of an imperforate shell designed to snugly fit in and completely fill the opening at the upper end of the 25 container and having an integral lower end wall and also having an integral flange at its upper

end which curves upwardly and outwardly and then downwardly about and beyond the upper end of the container, said umbrella top consisting of a metal plate having an outwardly and downwardly curving annular flange, an outwardly rolled seam uniting the edges of said flanges, and solder for sealing the seam and located on the outside of the top and out of contact with the contents of the container to which the cover is applied. 5

3. A cover for a container of the type having an upper open end and comprising a plug-like closure member and an umbrella top, the plug-like closure member being constituted of an imperforate shell designed to snugly fit in and completely fill the opening at the upper end of the container and having an integral lower end wall and also having an integral flange at its upper end which curves upwardly and outwardly and then downwardly about and beyond the upper 10 end of the container, said umbrella top consisting of an imperforate metal plate having an integral outwardly and downwardly curving annular flange, the edges of said flanges being interconnected, and an annular reinforcing ring disposed within and secured to the plug-like closure member and reinforcing the juncture of the shell thereof and the lower end wall. 15
